UNITED STATES PATENT OFFICE.

HAROLD E. YARROW, OF GLASGOW, SCOTLAND.

SUBMARINE VESSEL.

1,302,264.

Specification of Letters Patent. Patented Apr. 29, 1919.

Application filed October 30, 1917. Serial No. 199,309.

To all whom it may concern:

Be it known that I, HAROLD EDGAR YARROW, a subject of the King of Great Britain, residing in Glasgow, Scotland, have invented 5 certain new and useful Improvements Relating to Submarine Vessels, of which the following is a specification.

The invention relates to improvements for closing the top of the funnel of a submarine 10 vessel when it is intended to submerge the vessel.

According to the invention, a hinged valve is provided which can be operated from within the submarine to close the funnel 15 aperture when the vessel is submerged, and the means operating the valve are so arranged that at the first motion the oil fuel is shut off from the burners, the air doors are then closed to prevent the products of 20 combustion from escaping into the stokehold, and finally the funnel aperture is closed to prevent access of water.

In the accompanying drawing, Figure 1 is an elevation of the boiler, showing an example 25 of means for closing in succession the oil fuel supply, the air doors of the furnaces, and the funnel aperture; Fig. 2 shows on a larger scale the hinged funnel valve.

Figs. 2^a and 2^b show this valve cooled by 30 circulating water;

Figs. 3, 3^a, 3^b, 3^c and 3^d show means by which the funnel valve is closed automatically when the vessel dives.

Referring to Fig. 1, A is a boiler of the 35 water tube type, B the steam drum, C the uptake, D the funnel, and E a valve hinged at F for closing the top of the funnel when the vessel is submerged. G is a worm wheel rotated by a worm H adapted to open or 40 close the valve about its hinge F. The seating I of the valve is secured to the top of the funnel and packing J (Fig. 2) of leather, or other suitable material, serves to make the valve water-tight when the vessel is submerged. In the example shown, the worm H is rotated by spindles and bevel 45 gearing K. Assuming the valve E is in the open position, the rotation of a hand wheel L closes the oil fuel supply to the burners at a valve M by means of gearing N. When 50 this valve is completely closed a spring clutch T slips. While the hand wheel L is closing the valve M a worm wheel R, engaged by a worm S on the spindle operated by the hand wheel, moves from a position 1 to a position 2, but during this mo-

tion a connecting rod Q, pivoted to a radius of the wheel R and hinged to levers P operating air doors O of the furnaces, is only moved vertically by the small amount represented by the versed sine of the arc between positions 1 and 2. A further movement of the hand wheel L brings the wheel R into the position 3, in which the air doors O are closed. While the worm wheel R is moved from position 1 to position 3, the funnel valve E is moved from position 5 to position 6. A further rotation of the hand wheel will move the wheel R from position 3 to position 4 and will close valve E. The small vertical movement of the connecting rod Q between positions 3 and 4 is taken up by a spring X.

The oil fuel supply valve is first closed, then the air doors, and finally the funnel 75 valve. If these parts are to be closed simultaneously lost motion devices of the type described are not provided.

As shown in Figs. 2^a and 2^b, the funnel valve E¹ may be made hollow, so that water 80 entering at Y into the hollow spindle F¹, after passing through holes U drilled in the hinge to admit the water into the interior of the valve, escapes at X.

Referring to Fig. 3, a and b are, respectively, a worm and worm wheel corresponding to the worm H and worm wheel G of Fig. 1, c is a spindle to which the worm wheel b is secured and which is carried in two bearings d and d₁. The spindle c is 90 provided with a screw thread e engaging with an internal thread formed in the bearing d. Spring pins g, g₁ pass through slots in a projection f secured to the spindle c. The pins g, g₁ are held in position by a spring k (Fig. 3^a) of which the tension may be adjusted as required. On the hinge h of the funnel valve (which is not shown in the drawing) are projections m, m₁, n, n₁, shown, respectively, in Figs. 3^b and 3^c; which are 100 sections on the lines 1—1 and 2—2 of Fig. 3. The bearings d and d₁ are fixed to the funnel top l.

If the worm is rotated from the position shown, so that the top of the worm wheel b moves away from the reader, the pins g, g₁ will by contact with the parts o of the projections m raise the hinge h and with it the funnel valve. When the valve is fully open, the spindle c has moved so far to the left 110 that the pins g and g₁ are clear of the projections m and m₁ and are opposite the pro-

jections n and n_1 . The valve is kept open by the friction between the pins g , g_1 and the flat sides p of the projections n , n_1 . Lateral movement of the valve with the spindle c is prevented by guides on the funnel or by other suitable means.

If the vessel dives, the water presses against the valve, the hinge h is rotated without moving the spindle c , and the top 10 of the funnel is closed automatically. In order to insure that the valve is completely home on its seat the worm a may be rotated, so that the top of the worm wheel b moves toward the reader and the pins g , g_1 15 engaging with the parts q of the projections n firmly closes the valve. The spindle c has also moved to the right, so that the pins g , g_1 again engage with the projections m , m_1 . The pins g , g_1 need not be clear of the 20 projections n when the valve is closed, but they must be clear of the projections m in the open position, if the valve is to act automatically.

Having thus described the nature of the 25 said invention and the best means I know of carrying the same into practical effect, I claim:—

1. In a submarine vessel, a boiler, furnaces in the boiler with burners supplied with 30 oil fuel, air doors to the furnaces, a funnel, a hinged valve for closing the funnel, and means by the operation of which the oil fuel supply to the furnaces, the said air doors and hinged valve are closed in predetermined 35 sequence.

2. In a submarine vessel, a boiler, furnaces in the boiler with burners supplied with oil fuel, air doors to the furnaces, a funnel, a hinged valve for closing the funnel, and a 40 spindle by the operation of which the oil fuel supply to the burners is cut off, the said doors are then closed and then the hinged valve to the funnel is closed.

3. In a submarine vessel, a boiler, furnaces 45 in the boiler with burners supplied with oil fuel, air doors to the furnaces, a funnel, a hinged valve for closing the funnel, a spindle and a hand wheel operating said spindle, a valve for controlling the oil fuel supply, 50 gearing on said spindle for operating the valve, a spring clutch on the spindle, another spindle connected to said spring clutch, gearing on last mentioned spindle through which the air doors are operated, and also

gearing through which the funnel valve is 55 operated.

4. In a submarine vessel, a boiler, furnaces in the boiler with burners supplied with oil fuel, air doors to the furnaces, a funnel, a hinged valve for closing the funnel, a spindle 60 and a hand wheel operating said spindle, a valve for controlling the oil fuel supply, gearing on said spindle for operating the valve, a spring clutch on the spindle, another spindle connected to said spring clutch, 65 a worm on last mentioned spindle, a worm wheel engaged by said worm, a connecting rod pivoted to a radius of said wheel for operating the air doors of the furnace, and gearing on said last mentioned spindle 70 through which the funnel valve is operated.

5. In a submarine vessel, a boiler, furnaces in the boiler with burners supplied with oil fuel, air doors to the furnaces, a funnel, a hinged valve for closing the funnel, and 75 means by the operation of which the oil fuel supply to the furnaces, the said air doors and hinged valve are closed in predetermined sequence, the funnel valve being provided with hinges which are partly independent of the opening and closing means, so as to allow the automatic closing of the valve by the plunging of the vessel.

6. In a submarine vessel, a boiler, furnaces in the boiler with burners supplied with oil 85 fuel, air doors to the furnaces, a funnel, a hinged valve for closing the funnel, and means by the operation of which the oil fuel supply to the furnaces, the said air doors and hinged valve are closed in predetermined 90 sequence, the said means including a worm and worm wheel, a threaded spindle on said wheel adapted to move longitudinally when rotated by said wheel, bearings for said spindle, internal threads on said 95 bearings engaging with the threads on said spindle, projections on the hinge of the funnel valve, a projection on the spindle, and spring pins passing through said last named projection and adapted to engage with said 100 projections on the hinge of the funnel valve.

In testimony whereof I have signed my name to this specification in the presence of two subscribing witnesses.

HAROLD E. YARROW.
